UNITED STATES PATENT OFFICE

169,745

ACCORDION GRILL

Julio Giulietti, Brooklyn, N. Y., assignor to Giulietti Accordion Corporation, New York, N. Y., a corporation of New York

Application October 30, 1952, Serial No. 22,055

Term of patent 7 years

(Cl. D56—1)

To all whom it may concern:

Be it known that I, Julio Giulietti, a citizen of the United States of America and a resident of Brooklyn, county of Kings, State of New York, have invented a new, original, and ornamental Design for an Accordion Grill, of which the following is a specification, reference being had to the accompanying drawing, forming a part hereof, in which:

Fig. 1 is a top view of an accordion grill showing my new design.

Fig. 2 is a front view thereof.

Fig. 3 is an end view thereof.

Fig. 4 is a back view thereof.

I claim:

The ornamental design for an accordion grill, substantially as shown.

JULIO GIULIETTI.
